UNITED STATES PATENT OFFICE.

JOHN D. VANCE, OF CINCINNATI, OHIO.

HEATER-GRADE.

SPECIFICATION forming part of Letters Patent No. 367,255, dated July 26, 1887.

Application filed December 28, 1886. Serial No. 222,826. (No model.)

To all whom it may concern:

Be it known that I, JOHN D. VANCE, of Cincinnati, in the county of Hamilton and State of Ohio, have invented certain new and useful 5 Improvements in Heater-Grates, of which the following is a specification.

My invention relates to that class of fire-place heaters or open grates in which a double-heating effect is had—first, the direct heat 10 by radiation from the fuel in the fire-basket; second, the indirect heat from a current of air which is drawn from the outside of building, passed through certain heating-chambers surrounding the open grate, where it is highly 15 heated and discharged into the room where the fire-place is located, or in a room above it, through registers in the fire-place front or in the wall for the purpose; and it consists of certain novel constructions and devices, all of 20 which will be fully explained hereinafter.

In the accompanying drawings, Figure 1 represents a fire-place, partly in elevation and partly in section, containing my improvements; Fig. 2, a vertical transverse section on line $x-x$ of Fig. 1; Fig. 3, a horizontal section on line $y-y$ of Fig. 1; Fig. 4, a perspective view of the cast-iron fire-place back; and Fig. 5, a vertical transverse section of the upper portion, showing the construction of hot-air dampers or register-valves.

Similar letters of reference indicate similar parts.

A is the fire-place front; B, the fuel-basket, hung upon hooks b of the back C, which is 35 the grate-back proper and contains in a single casting the recessed back wall, c , and recessed side walls, $c' c'$, hood or deflector c'' , hooks $b b$, lateral flanges c^o , and throat c^s , through which the products of combustion of the fuel in the 40 basket B are conducted to the flue E.

F is a base-plate upon which the back C is mounted, and G a top plate fitting upon the nozzle of the throat c^s of the back.

H is a jacket, preferably of galvanized sheet-iron, riveted or otherwise attached to the flanges of plates F and G and to the lateral flanges c^o of the back C, the spaces between the jacket H, back C, and front A constituting the air-heating chambers I, into which air 45 from the outside of building is introduced 50 through the flue or duct J.

K is a damper or register-gate which opens and closes the duct J, actuated from the front of the fire-place by the shaft k and cranks $k' k''$, by means of which the secondary heating 55 effect of the fire-place may be controlled at will.

The upper part of the fire-place front A is provided with ornamental register-openings A', the exit of the heated air through which 60 is controlled by the damper or valve L in the space I at the top of the heater, while another damper or valve, M, controls the exit of heated air from the heating-chambers I to the duct N, which leads to the room over the grate. 65

The dampers L and M are connected by a link, l, by means of which they are alternately opened and closed simultaneously, or the opening of the damper L is accomplished by the closing of the damper M, and vice versa, 70 or the heated air may be divided at will between the room in which the fire-place is located and the room above, in which the duct N debouches, both dampers being manipulated by the lever O, pivoted to the upper 75 part of the front A.

Referring to Fig. 5, the full lines show the register in the upper part of the front covered by the damper L and the duct N open, while by dotted lines the duct N is shown covered 80 by the damper M and the register-openings in the front A open.

In all previous constructions of grates with which I am familiar the fire-place back C is of several plates bolted or riveted together, and, 85 however tight such joints may be originally, the slightest warping of the plates when subjected to heat permits of the passage of the products of combustion from the fire-place proper into the heating-chambers I, and vice 90 versa. When the gases of combustion pass into the heating-chambers and are discharged into the rooms to be heated, the atmosphere which the occupants breathe is charged with carbonic-acid gas, and when the heated air 95 passes through the defective joints of the back into the fire-place proper the secondary effect of the heater is lost up the chimney, the heated air and gases of combustion flowing together through the throat c^s and up the flue E. 100

By my construction all joints in the back are avoided and a transfer of the hot gas of com-

bustion to the heating-chamber I or a loss of heated air up the chimney is entirely prevented.

Referring to Fig. 5, c^5 is a damper hinged 5 to the top of the throat c^3 and actuated by the lever c^6 , which turns on the pivot c^7 and engages with the arm on the lower side of the damper-plate. By means of the toothed rack c^8 at the side of the throat the damper may be 10 opened more or less in operating the grate, and may be closed entirely in the summer season to prevent the blowing of soot and dust down the chimney-flue into the room.

In the construction of the back C tiles c^1 15 are set in the recesses of the back and side walls, c^4 , to intercept the radiant heat from the fuel in the basket B, to be secured in position in any convenient manner.

Having described my invention, what I 20 claim is—

1. In a fire-place heater of the character described, a grate-back composed of a single

casting integral with the throat c^3 , for the escape of products of combustion, the rear and side recessed walls, c^4 , to receive the back 25 and side tiles c^1 , the inwardly-projecting hooks b , for supporting the fuel-basket, and the lateral flanges c^9 , for the attachment of the sheet-iron jacket, substantially as described.

2. In a fire-place heater of the character described, a grate-back, C, cast in a single piece with the recessed back walls, c , sides c' , inwardly-projecting fuel-basket supporting hooks b , hood c^2 , contracted throat c^3 , and flanges c^9 , for attaching the sheet-iron jacket H, 30 35 substantially as described.

In testimony whereof I have signed my name to the foregoing specification in the presence of two subscribing witnesses.

JOHN D. VANCE.
